HOLDER FOR BREAD OR THE LIKE FOR ATTACHMENT TO DISHES

Joana B. Bernstine, 538 W. 75th St., Los Angeles, Calif.

Filed July 27, 1964, Ser. No. 81,030

Term of patent 14 years

(Cl. D44—10)

FIG. 1 is a view in perspective as viewed from the front of a holder for bread or the like for attachment to dishes embodying my new design;

FIG. 2 is a cross-sectional view taken at the center of FIGURE 1 on line 1—1.

I claim:

The ornamental design for a holder for bread or the like for attachment to dishes, substantially as shown.
